UNITED STATES PATENT OFFICE.

FREDERICK KINDE, OF SARATOGA, WYOMING, ASSIGNOR OF ONE-THIRD
TO JOHN C. DAVIS, OF RAWLINS, WYOMING.

APPARATUS FOR PREVENTING SINKING OF SHIPS AND FOR RAISING SUNKEN VESSELS, &c.

SPECIFICATION forming part of Letters Patent No. 557,396, dated March 31, 1896.

Application filed December 30, 1895. Serial No. 573,760. (No model.)

To all whom it may concern:

Be it known that I, FREDERICK KINDE, a citizen of the United States, residing at Saratoga, in the county of Carbon and State of Wyoming, have invented new and useful Improvements in Apparatus for Preventing the Sinking of Ships and other Water-Craft and for Raising Sunken Vessels and other Submerged Objects, of which the following is a specification.

My invention relates to apparatus for preventing the sinking of ships and other water-craft and for raising sunken vessels and other submerged objects; and it consists in an inflatable gas, air, and water tight bag, of any suitable size and form, to be secured, in any required number, to water-craft or other objects, and capable of inflation, (preferably by electrical explosion of gas-generating chemicals contained in a storage-receptacle inclosed by the bag and communicating therewith,) so as to buoy up a vessel in case of emergencies—such as collisions, springing a leak, &c.—and to be available also for raising sunken vessels and other objects.

It is more especially the purpose of my invention to provide inflatable buoying apparatus, conveniently arranged for storage aboard a ship, and which will be always ready for speedy and effective use to prevent sinking of the vessel in a sudden emergency, thereby aiding greatly in the saving of life and property at sea.

The invention is illustrated in the annexed drawings, in which—

Figure 1 is a partly-sectional view of my inflatable buoying apparatus for sustaining, raising, and preventing the sinking of leaky ships, vessels, boats, and other water-craft. Fig. 2 is a partly-sectional view of a receptacle or holder for explosive gas-generating chemicals inclosed in the inflatable buoy or bag and provided with means for electrical ignition.

In carrying my invention into effect, I provide for the attachment to the sides of ships, vessels, boats, or other water-craft a sufficient number of inflatable gas, air, and water tight bags, the capacity and number of which may be suitably proportioned to the size, weight, and tonnage of the vessel, craft, or other ob-

ject to be held afloat. Each inflatable bag or sack, designated by the numeral 1, is composed of a suitable waterproof and air or gas tight material, such as canvas covered with rubber. If desired, the bag may be lined with asbestos, or be otherwise made fireproof. The bag or sack should be made of sufficient strength to withstand a pressure of, say, twenty pounds to the square inch, or any other required amount. On its outside the bag is preferably braced by a network of cords 2, secured in any suitable manner.

At a convenient point there is securely fastened in an aperture of the bag material an internally screw-threaded collar 3 of brass, bronze, or other metal.

A steel cable 4 is vulcanized or otherwise secured in the seam of the sack or bag 1, and has its ends fastened to rings 5 on opposite sides of the collar 3, the said cable being extended entirely around the bag or sack. On one side of the sack, opposite the collar 3, the cable 4 is extended outward and formed into a ring 6 to afford means for attaching the bag to an object or vessel to be raised in the water or prevented from sinking. A stay or brace rod 7 may be fastened to the projecting portion or arms of the cable between the ring 6 and the bag. Two or more heavy bands or strips 8 of canvas or other suitable material are extended around the bag 1 and vulcanized thereto and are also extended over the cable 4, thus further strengthening the bag or sack and equalizing the pulling or holding power of the cable.

The internally screw-threaded collar 3 is arranged for insertion and secure engagement of a metal screw-plug 9 having a flanged head 10 and a handle 11 by which the plug may be screwed into place. The plug 9 may be fastened to the collar 3 by means of bolts passed through the flange 10, as well as by the screw-threaded engagement of plug and collar, or they may be fastened together by any other suitable means. This plug 9 affords support for one or more metal tubes 12 13 to contain the gas-generating material for use in effecting inflation of the bag or sack. In Fig. 2 I have shown two of these tubes, but any required number may be provided according to the quantity of chemicals to be con-

sumed in producing the gas. Where two tubes are provided, as shown, one tube may be longer than the other. Both tubes are closed at the ends which are secured to the 5 plug 9, and their other ends are open for reception of the chemicals to be packed therein and for escape of the gases generated when the tube contents are ignited or exploded. The tubes 12 and 13 may be of any size or capacity required. To the end of the longer tube 12 is fastened a metal hood 14 to protect the bag 1 from any flame issuing from the tubes, the said hood being sufficiently wide to extend across both tubes. As a means for 15 attaching the hood 14 it is provided with two spring-arms 15 detachably secured to the tube 12 by pins 16 or otherwise.

In the metal plug 9 is a rubber insulating-plug 17 for passage of electric wires 18 that 20 extend outside the tube 12 and connect with a cartridge 19 in the open end of said tube, the cartridge being charged with powder-dust, into which may be inserted a section of platinum wire, in connection with the wires 18, for 25 giving a spark to ignite the contents of the tube. An asbestos-covered fuse 20 is connected with the contents of tube 12 near its closed end and is extended thence to the contents of the tube 13 at a point near the open 30 end of said tube. If additional tubes are employed for storage of a larger quantity of gas-producing material, the several tubes will be connected by fuses in like manner, so that the contents of the tubes may be ignited or 35 exploded in succession, and not all at once.

In the plug 9 and communicating with the interior of the bag 1 is a safety-valve 21, to prevent an undue accumulation of pressure from the gases generated within the bag.

40 The tubes 12 13 being charged with chemicals or a chemical compound capable of generating a sufficiency of light buoyant gas on ignition or explosion, and the several described attachments having been properly adjusted, the plug 9 and attached parts will be securely inserted in the collar 3 of the bag 1, and the latter will then be placed in position and the wires 18 connected with a battery or source of electricity.

50 When the bag 1 is fastened to an object under water or to a vessel in danger of sinking, an electric current may be supplied through the wires or conductors 18 to ignite or explode the gas-producing contents of the 55 tube or tubes. As soon as the contents of the tube 12 are nearly consumed the fuse 20 will fire the contents of tube 13, and so on if other similar tubes are provided. The gas thus generated will inflate the bag and buoy up 60 any object to which it is secured. It is intended to so fasten the bags to a ship that they will be out of the way and not interfere with the navigation of the vessel. If a ship is run into, stove in, or springs aleak and is 65 about to sink, the battery may be worked, the bags inflated almost instantly, and the vessel be thereby held afloat. The bags or sacks

are to be made any dimensions deemed necessary and may be employed in any required number attached to the sides or interior of a 70 ship in the most convenient or desirable position. If desired, the safety-valve 21 can be removed and a pipe be screwed on in its place as a means for reinflating the sack, if found necessary, without detaching it from the object to which it is fastened. 75

By use of the inflatable bags and their gas-generating attachments sunken ships and any submerged objects may be raised to the surface, and they may be used at a moment's 80 notice in case of accident to prevent the sinking of water-craft.

The gas-generating material that I prefer to employ for inflating the bag is composed of blasting-powder, three parts, and coal-oil, 85 one part; but other suitable gas-generating compounds may be used. The blasting-powder may contain saltpeter, 74.83 parts, charcoal, 13.31 parts, and sulfur, 11.86 parts, or thereabout. 90

In the construction of the inflatable bag 1 any required number of steel cables may be employed, each extended around the bag and vulcanized into the bag-seams, as already described with reference to the steel cable 4 95 shown in the drawings.

What I claim as my invention is—

1. In apparatus to raise sunken vessels and prevent the sinking of ships, the combination of an inflatable gas-tight and water-tight bag 100 adapted to be secured to water-craft or submerged objects, a holder supplied with combustible gas-producing material and removably held within said bag, a cartridge in said holder, and electrical devices connected with 105 said holder for igniting the said cartridge and gas-producing material, to inflate the bag, substantially as described.

2. In apparatus to raise sunken vessels and prevent the sinking of ships, the combination 110 of an inflatable gas-tight and water-tight bag adapted to be fastened to water-craft or submerged objects, a collar secured in an aperture in one part of said bag, a plug detachably held in said collar and carrying on its 115 inner side a tube supplied with combustible gas-producing material, a cartridge in said tube, electric wires connected with said cartridge, and a hood for the open end of said tube, substantially as described. 120

3. In apparatus to raise sunken vessels and prevent the sinking of ships, the combination of an inflatable gas and water tight bag, a steel cable surrounding said bag and vulcanized in a seam thereof to serve as a means for 125 strengthening the bag and attaching it to water-craft or submerged objects, a holder for combustible gas-producing material removably inclosed in said bag, electrical devices for exploding or igniting said material, and 130 means for protecting the interior of the bag from flame and sparks, substantially as described.

4. In apparatus to raise sunken vessels and

prevent the sinking of ships, the combination of an inflatable gas-tight and water-tight bag adapted to be secured to water-craft or submerged objects, a collar fastened in an aperture in one part of said bag, a plug detachably secured in said collar and provided with a safety-valve, tubes secured to the inner side of said plug to contain a gas-producing material and each communicating at one end 5 with the interior of the bag, a cartridge in the open end of one of said tubes, electric wires connecting with said cartridge, a fuse ex-

tended from the material in the closed end of one tube to the material in or near the open end of the other tube, and a hood for the open 15 ends of said tubes, substantially as described.

In testimony whereof I have hereunto set my hand in presence of two subscribing witnesses.

FREDERICK KINDT.
